UNITED STATES PATENT OFFICE.

EVAN BARNETT BASCH, OF SAVANNAH, GEORGIA

PHONOGRAPHIC DICTATING-MACHINE.

1,278,565.

Specification of Letters Patent. Patented Sept. 10, 1918.

Application filed September 24, 1917. Serial No. 193,007.

To all whom it may concern:

Be it known that I, EVAN BARNETT BASCH, a citizen of the United States of America, and a resident of Savannah, 5 county of Chatham, and State of Georgia, have invented certain new and useful Improvements in Phonographic Dictating-Machines, of which the following is a full and clear specification.

10 My invention relates to dictating machines and more particularly to devices for automatically indicating upon a record when an error in dictating has been made.

In dictating machines of any make words 15 recorded on the wax cylinder cannot be changed, or erased, so if an error in dictation is made, the dictator must afterward speak the corrected words, and some signal must be given to the typist, so he will know 20 an error has been made at a certain point on the cylinder, and will then be able to determine the correct words to transcribe.

At present this is ordinarily accomplished 25 by providing a printed card with a scale corresponding to the progress of the recorder across the cylinder, so that a pencil mark or check at a point on the card will call attention to a correction at a corresponding point on the cylinder.

30 On the Edison dictating machine for instance, the printed card is placed in a holder which travels with the record, and a short rule fixed to the machine at right angles to the path of the card automatically indicates 35 on the card the position of the recorder on the cylinder, consequently when an error has been made in dictating the dictator draws a line across the card at the point where the fixed rule is, thereby indicating 40 that an error has been made at that point.

Various other similar devices are in use 45 on other makes of machines but in every case the dictator is obliged to stop and make some mark on the record card indicating an error. This is not only an annoyance and a loss of time but it oftentimes causes him to lose the thread of thought and necessitates him rereading a portion of the cylinder to find where the dictation ended.

50 By the device about to be described these objections are eliminated and means are provided whereby when the dictator makes an error it is only necessary for him to press a button located conveniently on the speaking tube, which will automatically indicate on 55 the record card that an error has been made.

Hence it will be seen that the dictator will not be obliged to stop dictating and with a pencil indicate the error and then resume his dictation but need only press the button, 60 which automatically makes the mark.

There are various means for accomplishing this but I have shown only one. It will be understood that various changes may be made on the details of construction so as to 65 adapt this invention to the different makes of machines. I have shown my device including a fixed record card and the marker as being secured to the recorder and moving therewith but it is obvious that the record 70 card may be fixed to the recorder and the marker stationary.

The invention will be more thoroughly understood by reference to the specification and drawings, in which:—

75 Figure 1 is a plan view of a dictating machine showing my invention attached.

Fig. 2 is a transverse section taken on line 2—2 of Fig. 1.

Fig. 3 is a fragmentary view partly in section, of the end of the speaking tube.

Fig. 4 is a detail sectional view of the record card and attaching means.

Fig. 5 is a diagrammatic view of the device; and

Fig. 6 is a detail view of a modified form of any device.

The numeral 1 represents the ordinary dictating machine of the Edison type and 90 2 the usual cylinder upon which the dictation is recorded. The recorder 3 has the usual tube 4 terminating in a mouth-piece 5 and having secured near the mouth-piece a finger grip 6, and the cylinder controlling button 7. As is customary in machines of this kind the recorder 3 during its operation of recording moves to the right of the cylinder hence I have shown the device for automatically marking the record card as secured to the recorder and comprising a solenoid 8 having a movable core 9 provided with an extension 10 for holding a suitable pencil 11.

To normally keep the core in its extended position I provide a spring 12 bearing 105 against a collar 13 formed on the extension 10 and the face of the solenoid. By this construction it will be seen that when the solenoid is energized it will attract the core and draw it inward compressing the spring 12 between the collar 13 and the face of the solenoid and move the marker in a corre- 110

sponding direction across the record card, thereby indicating that at that point an error has been made.

I can secure the solenoid to the recorder 5 in any suitable manner but I have shown the securing means as comprising a metal strap 14 shaped to circumferentially secure the solenoid and then clamped around the recorder by means of a screw 15.

10 The record card is here shown as a cellular card 16 secured by suitable supports 17 and screws 18 at each end to the frame 19 of the machine as shown.

The solenoid may be energized by any 15 source of power. It may for instance be connected to the motor circuit or it may be supplied by a separate source of power S, as indicated diagrammatically in Fig. 5. The source of power may be located conveniently 20 in the casing inclosing the machine.

The wires 20 which connect the solenoid to the source of power and to the circuit closer are for convenience located on the tube 4.

25 Located at the end of the tube and preferably adjacent the finger grip 6 is a switch adapted to close the circuit between the solenoid and the source of power. This switch is shown as comprising a contact 21 and a 30 spring held contact 22 provided with an operating button 23. The switch is normally open but when it is desired to energize the solenoid it is only necessary for the dictator to press the button 23, thereby closing the 35 circuit to said solenoid.

From the foregoing it is seen that when 40 an error in dictating has been made the dictator need only close the circuit by means of the button 23, thereby energizing the solenoid 8, and consequently drawing the marker 11 across the record card 16 indicating thereby that an error has been made at a corresponding point on the cylinder. This operation need not interrupt the dic-

tation as it requires only a fraction of a second and the dictator may continue with his dictation, giving it in its corrected form.

In Fig. 6 I have shown a modified form of the marker operator, the core 9^a having secured thereto an L-shaped arm 10^a carrying 50 at one end the marker 11^a. The other arm of the L-shaped member is pivoted at 25 to a support 26 secured to the solenoid and is provided with a spring 27 to normally keep the marker in its extended position.

55 It is obvious that various changes and modifications in details of construction may be made without departing from the scope of my invention.

What I claim is:—

1. In a dictating machine, a record card, a marker, a solenoid, means for normally holding said marker in its inoperative position, and means controllable at a distance for energizing said solenoid and thereby operating said marker. 65

2. In a dictating machine, a record card, a marker, means for normally holding said marker in its inoperative position, and means controllable at a distance for operating said marker. 70

3. In a dictating machine, a record card, a marker normally in inoperative position, means for moving said marker into operative position comprising a solenoid and means controllable at a distance for energizing said solenoid. 75

4. In a dictating machine, a record card, a marker normally in inoperative position and adapted to be drawn across said record card, a solenoid adapted when energized to operate said marker, and means controllable at a distance for energizing said solenoid to operate said marker. 80

85 In testimony whereof I hereunto affix my signature.

EVAN BARNETT BASCH.
